UNITED STATES PATENT OFFICE.

JOHN M. LARSON, OF CHICAGO, ILLINOIS, ASSIGNOR TO NATIONAL REGULATOR COMPANY, OF CHICAGO, ILLINOIS, A CORPORATION OF ILLINOIS.

BOILER AND DAMPER REGULATOR FOR BOTH STEAM AND HOT WATER.

1,387,853.

Specification of Letters Patent. Patented Aug. 16, 1921.

Application filed October 22, 1917. Serial No. 197,799.

To all whom it may concern:

Be it known that I, JOHN M. LARSON, a citizen of the United States, residing at Chicago, in the county of Cook and State 5 of Illinois, have invented new and useful Improvements in Boiler and Damper Regulators for Both Steam and Hot Water, of which the following is a full, clear, concise, and exact description, reference being had 10 to the accompanying drawing, forming a part of this specification.

My invention relates to improvements in boiler and damper regulators for both steam and hot water, and has for its object the 15 production of a device in which the diaphragm controlling the damper or boiler can be removed without interfering with the boiler itself, or without the necessity of drawing the fire and water.

20 A further object is the production of a device of simple and efficient construction and one not liable to disarrangement.

These and such other objects as may hereinafter appear are attained by my device, an 25 embodiment of which is illustrated in the accompanying drawings, in which—

Figure 1 represents a side elevation of my device partly in section;

Fig. 2 represents a top plan view of Fig. 1. 30 Like numerals of reference indicate like parts in the several drawings.

Referring now to the drawings, *a* represents the outer shell of a boiler having a threaded opening *b*, within which is screwed 35 a well *c*. This well has a closed bottom and extends well within the receptacle. Above the nut *d* the outer periphery of the wall of the well is flared outwardly at *e*, forming a circumferential groove *f*, adapted to receive a 40 the ends of threaded screws *g*—*g*¹ which hold a supporting cap *h* in position on the well. The bottom flange *i* of the supporting cap is adapted to rest upon the top of the nut *d*. The cap *h* is contracted at its upper 45 portion forming a passage *j* and a pair of yokes *k*—*k*¹ extend upwardly from the top of the cap and are preferably formed integral therewith.

A plurality of diaphragms *l* are secured 50 together and a centrally disposed screw threaded stem *l*¹ is mounted on the upper unit of the diaphragm. This unitary system of diaphragms is screwed into the diaphragm support *m* within which is screwed 55 a screw threaded rod *n*, passing up through

the constricted part *j* of the cap and terminating in the screw threaded end *o*, on which is mounted a lever connection *p*. The lever *q* is pivotally mounted on this supporting member *p* at *p*¹ and fulcrums on the pin 60 *r* passing through openings in the yoke *k*¹. On the opposite side the lever *q* passes between the guiding yoke members *k*. Suitable counterweights *q*¹—*q*¹ are mounted on either side of the device and are adapted to 65 be moved to accommodate any desired pressure.

A washer or packing *s* surrounds the stem or rod *n* fitted within the constricted portion and prevents the escape of heat from 70 within the well, and prevents the entry of dust and dirt into the interior of the receptacle. This is very necessary as the device when used is in a place exposed to all kinds of dirt and the device would be quickly 75 clogged up and rendered unreliable unless a precaution of this character was taken. In applying my device, the cap and diaphragm are then placed within the well.

In applying my device it is simply necessary to bore a hole in the casing of the 80 boiler, tap it and screw in the well *c*. The cap and diaphragms are then placed within the well, the stem passing up through the cap *h* which is dropped over the top of the 85 well. The screws *g* are then inserted and as they are screwed home, their ends strike against the inclined portion of the groove *f*, forcing the cap down tightly on to the nut *d*. The tighter the screws are turned in, the 90 tighter would be the fit between the cap and the well.

It will be noted that this well is a dry one and when in place, the diaphragms within the well will be entirely below the level 95 of the fluid within the boiler. The diaphragms *l* are filled with ether or some volatile liquid that will be readily affected by change in temperature. It is apparent, therefore, that in the event of a leak in the 100 diaphragms, or any failure of the device to register properly, and it becomes necessary to inspect the diaphragms or take them out, it is simply necessary to loosen the two screws *g*, lift off the top and take the diaphragms from the well. The individual diaphragms may then be unscrewed from 105 the top and replaced without opening the boiler at all.

A device of this character is very valuable.

ble for the reason that in the other forms now in use, the diaphragms are submerged in the liquid itself, and in order to take them out for inspection, or repair, or replacement, it is necessary to open up the boiler. In the case of a boiler used for hot water heating system, it would be necessary to first draw the fire, then take out the water from the boiler down below the level of the opening. It will be necessary to go around to all the radiators from the top to the bottom of the building, open the cocks and valves, and later going around and closing them again, and then when the device is put in and ready to start up again, additional cold water must be put in, the fire started and after the fire gets going, it is again necessary to go around to all the radiators, open up the cocks and valves in order to let out the cold air, thus causing an inconceivable amount of bother and annoyance to tenants, to say nothing of the time during which the whole system is out of service, and those requiring heat are left in the cold.

By the use of this device, in the event that anything happens to the diaphragms, the diaphragm itself can be removed and sent out for repairs and returned in a very short time, or the user can have an extra set of diaphragms on hand so that the old diaphragm can be replaced in a very few moments. Heretofore, it has been necessary to take out the entire apparatus and ship it for repairs, an expensive and bothersome task, while in the present case all that will be necessary to be sent away would be the diaphragms themselves, weighing but a few ounces.

It will be noted that the diaphragms are normally collapsed and as a unit can be detached from the head and also that at all times when the diaphragms are in place, they are within the well and below the inner face of the boiler and are consequently unaffected by the temperature on the outside.

A further advantage incident to the use of my device is that there is no change in the position of the fluid other than its expansion and contraction within the diaphragms themselves. There is no fluid entering within any of the chambers rising and falling therein as in other devices which corrode the different parts, rendering them difficult to take apart in the event that it is desired to disassemble them, but also cause them to rapidly deteriorate.

Another valuable feature that is present in my device and absent in all other is the entire lack of solder except that used in assembling the separate diaphragm disks into a unitary structure.

Another valuable feature that is present in my device is the fact that the cap of the well can be secured thereon in any desired

position relative to the line of the damper 65 yoke. In other devices it is necessary to have the whole device accommodate itself to the line of the lever and to do this, it is often impossible to secure the members tightly together, as the device must always be given a full turn and when it is screwed securely in place, it is by chance, if at all, that it is in the proper relative position with respect to the line of the lever. Hence, it is necessary to unscrew it a portion of a 75 turn in order to accommodate the line. In my device, however, the top being separable from the well, and adjustably mounted thereon, the well itself is securely screwed into place and then the cap placed thereon 80 in proper position and secured by means of the screws *g*.

While my device is extremely simple, it is very effective and it is evident that other forms than that illustrated in the drawings may be adopted without departing from the spirit of my invention.

Having thus described my invention, what I claim as new and desire to secure by Letters Patent is:—

1. In a device of the class described, a well adapted to be screwed within the outer shell of a boiler, a tubular open-ended cap removably mounted on said well and containing a dust-excluding packing, a series 95 of diaphragms fitting within said well, a stem secured at its lower end to said diaphragms and extending through said tubular cap and packing and means whereby the expansion and contraction of said diaphragm may be utilized to operate a damper or like device.

2. In a device of the class described, a well closed at one end and open at its other end and adapted to have its closed end inserted into a boiler, the open end being provided with an annular flange, a tubular open-ended cap adapted to fit over said open end of the well and provided with clamping means for engaging the flange thereon 105 in such manner as to permit the cap to be rotated with respect to the flange, an elastic guiding dust-excluding packing or washer in the upper end of the tubular cap, a stem extending down through said washer 110 and into the well, an expandable diaphragm structure confined in the well and adapted to actuate said stem, and means mounted on the outer end of the cap and connected to said stem at a point beyond the washer 120 for connection with the device to be actuated by the reciprocation of said stem.

In witness whereof, I have hereunto subscribed my name.

JOHN M. LARSON.
